E. HIGGINBOTTOM

MACHINE FOR SEPARATING PARTICLES BY SPECIFIC WEIGHT

Filed Aug. 14, 1924

FIG. 1.

FIG. 2.

FIG. 3.

Inventor
E. Higginbottom
by *John Meiss Atty.*

UNITED STATES PATENT OFFICE.

EDWIN HIGGINBOTTOM, OF LIVERPOOL, ENGLAND.

MACHINE FOR SEPARATING PARTICLES BY SPECIFIC WEIGHT.

Application filed August 14, 1924, Serial No. 732,069, and in Great Britain August 14, 1923.

This invention relates to machines for separating grains, stones, seeds or granules of materials through their varying specific weight by means of a moving medium such as a liquid, and of the type in which it has hitherto been usual to actuate such medium by mechanism outside of the separator.

According to this invention, more regular separations, a greatly simplified procedure, 10 and economy both in power required to drive the machine and in the space occupied, is obtained, by making the machine self-contained in the manner hereinafter more particularly set out and illustrated in the accompanying drawings.

In the drawings Figure 1 is a view in part sectional elevation, Figure 2 is also a view in part sectional elevation but illustrating a modification, while Figure 3 is a detail 20 view.

Referring to the drawing the separator is constructed with contiguous vertical or nearly vertical walls 1, 2, 3, the walls 1 and 2 being spaced to provide a passage 5, and the 25 walls 2 and 3 being spaced to provide a passage 7. The walls 1, 2, and 3, are concentric and wall 1 is preferably provided by the vertical surface of a circular member arranged to rotate and provided below the 30 wall with vanes 4 arranged to induce an upward or lifting movement direct to the separating medium in the passage 5 such medium after performing the desired separation passing through a pervious screen or 35 screens 6 within the machine and returning to its starting point by a contiguous passage 7 to revolving vanes 4. 8 is a guiding bearing for the central shaft 9 in order to keep walls 1 and 2 equidistant and past which the 40 separating medium flows equally at all points of its circumference.

The central shaft 9 carries impellers 11 and an annular plate 12 opening up the material under treatment. 13 is a perforated 45 or plain revolving drum on shaft 9 and which carries lifters 14 which raises the material under treatment from the separating medium and delivers the same through a suitable spout 15. As noted in the drawing, 50 these lifters 14 are formed by oblique or helical plates carried on the periphery of drum 13. Motion is imparted to the machine by driving pulleys 16. The material to be separated is fed into the centre of drum 55 13 through which it falls directly by grav-

ity into the separating medium and to the impellers 11 and annular plate 12 the lightest material being lifted by the separating medium to the periphery of the drum 13 by means of the lifters 14 and thence 60 through the spout 15, whilst the heavier matter according to the velocity of the separating medium descends through the passage 5 and collects in the bottom of the casing from which it may be discharged when 65 required by opening the valve 17.

The level of the separating medium is maintained at about that indicated by the dotted line A, A. Vanes 18^x serve to steady the admixture of material and medium during the process of separation. An adjustable siphon pipe 19 is employed to maintain the desired level for the liquid medium, whilst a suitable inlet which can be inserted at any convenient position preferably at 70 the opposite side of the machine to siphon pipe 19 or through the drum 13, is provided for supplying fresh liquid to replace that carried away by the material under treatment.

In some cases the walls 1 may be carried up to or beyond the plate 12 and the impellers 11 combine with the same, or the plate 12 may be made one with the steady- 75 ing vanes 18.

The impellers 11 (see Fig. 3) serve the treble purpose of immersing and washing the incoming grain and of automatically keeping clean the surface of the pervious screen 6 by the wash of the water from their 80 ends.

According to a modification the whole or a part of the eliminating scrapers or lifters 14 are driven at a higher speed than that of the central shaft 9. One way in which 85 this may be accomplished is shewn in Figure 2 of the drawing in which drum 13 with the scrapers or lifters 14 has superimposed a second similar drum 18 with scrapers or lifters 19 to receive the grain from the drum 13 and lifters 14 and submit it to a higher velocity, or I may prefer in some cases to dispense with the slower revolving drum 13 and raise the grain with the faster running drum 18 from the water line AA and to deliver the 90 same through the spout 15.

The higher speed drum 18 is carried by a loose sleeve 20 with a bearing collar 21 upon shaft 9 and is driven by gear wheels 22, 23, and 24 from wheel 25 which is fixed to shaft 100 110

9. 26 is an inside revolving hopper to receive the grain fed in and deliver same to water line AA and the impellers 11.

What is claimed is:—

- 5 1. A separating machine, comprising a casing, means within said casing adapted to receive the material to be treated and throw it outwards, means in said casing for forcing liquid upward into the outwardly flowing stream of material, and a casing outside said casing, and forming therewith a conduit for the return liquid from the upper part of the machine to the lower part and the liquid forcing means.
- 15 2. A separating machine, comprising means adapted to receive the material to be treated and to throw it outwards, means for forcing liquid upward into the outwardly flowing stream of material and a rotary drum with blades arranged obliquely on the periphery of same and extending from a point within the surface of the liquid to a point well above same and adapted to lift and elevate the material from the level to a delivery part above.
- 25 3. A separating machine, comprising means adapted to receive the material to be treated and to throw it outwards, means for forcing liquid upward into the outwardly flowing stream of material, a rotary drum with blades arranged obliquely on the periphery of same and extending from a point within the surface of the liquid to a point above same; and a second rotary drum similar to and above said first mentioned drum,

said drums being adapted to be revolved at relatively different speeds and serving to elevate the material from the liquid for delivery.

4. A separating machine, comprising a container, including an outer wall, an inner wall spaced from said outer wall, the upper portion of the inner wall being of screen formation to provide communication on opposite sides of the inner wall, a central rotating member arranged concentric with and inwardly of the inner wall, a liquid circulating element carried by and operative with said rotating member, and a material lifter operating at the surface of the liquid and above the same, impellers operating in the liquid, and a plate underlying said impellers.

5. A separating machine comprising means adapted to receive the material to be treated, rotary means below said first mentioned means adapted to receive the material and to mechanically centrifugally throw the material outwards, a wall or surface disposed outside and around the periphery of the rotary means and spaced therefrom, and liquid forcing means below the rotary means for forcing the liquid upward through the space between the said periphery and the wall or surface into the outwardly flowing stream of material.

In testimony whereof I have signed my name to this specification.

EDWIN HIGGINBOTTOM.
